Primary Examiner — Holly Baynam*Assistant Examiner* — Rhea Shields(74) *Attorney, Agent, or Firm* — Altera Law Group, LLC(57) **CLAIM**

The ornamental design for a mobile cart, as shown and described.

DESCRIPTION

FIG. 1 is a top perspective view of a mobile cart.

FIG. 2 is a front elevation view thereof.

FIG. 3 is a rear elevation view thereof.

FIG. 4 is a side elevation view thereof.

FIG. 5 is the other side elevation view thereof.

FIG. 6 is a top plan view thereof; and,

FIG. 7 is a bottom plan view thereof.

In the drawings, the broken lines depict unclaimed subject matter only and form no part of the claimed design.
